DESIGN FOR A BOOK END

William E. Lind, Dallas, Tex., assignor to Guiberson Diesel Engine Company, Dallas, Tex., a company of Delaware

Application November 15, 1944, Serial No. 116,350

Term of patent 14 years

(Cl. D33—4)

To all whom it may concern:

Be it known that I, William E. Lind, a citizen of the United States, residing at Dallas, in the county of Dallas and State of Texas, have invented a new, original, and ornamental Design for Book Ends, of which the following is a specification, reference being made to the accompanying drawing, forming a part thereof:

Fig. 1 is a top plan view of a book end showing my new design.

Fig. 2 is a front elevational view thereof, and Fig. 3 is a side elevational view taken at right angles to Fig. 2.

I claim:

The ornamental design for a book end, as shown.

WILLIAM E. LIND.
